DESIGN FOR A BOTTLE

Benjamin Lewis, New York, N. Y., assignor to Lionel Rothschild, Dallas, Tex.

Application August 10, 1945, Serial No. 121,362

Term of patent 14 years

(Cl. D58—9)

To all whom it may concern:

Be it known that I, Benjamin Lewis, a citizen of the United States, residing at New York, in the county of New York and State of New York, have invented a new, original, and ornamental Design for a Bottle, of which the following is a specification, reference being had to the accompanying drawing, forming part thereof.

In the drawing:

Fig. 1 is a front elevational view of a bottle, showing my new design;

Fig. 2 is a side elevational view thereof; and
Fig. 3 is a rear elevational view thereof.

I claim:

The ornamental design for a bottle, as shown.

BENJAMIN LEWIS.
